[57] CLAIM

The ornamental design for an X-cable between a tv and a computer, as shown and described.

DESCRIPTION

FIG. 1 is a perspective view of an X-cable between a TV and a computer incorporating my new design in full lines with the broken lines showing of enviromental association matter being for illustrative purposes only and forming no part of the claimed design;

FIG. 2 is a top plan view thereof in full lines, and the enviromental matter shown in broken lines;

FIG. 3 is bottom plan view thereof in full lines, and the enviromental matter shown in broken lines;

FIG. 4 and 5 are, respectively, front and rear views thereof; and,

FIG. 6 and 7 are, respectively, right and left side views thereof in full lines, and the enviromental matter shown in broken lines.
